[57] CLAIM

The ornamental design for a paper binding machine, as shown and described.

DESCRIPTION

FIG. 1 is a right side view of a paper binding machine, showing my new design;

FIG. 2 is a left side view thereof;

FIG. 3 is a rear elevational view thereof;

FIG. 4 is a front elevational view thereof;

FIG. 5 is a top plan view thereof;

FIG. 6 is a bottom plan view thereof;

FIG. 7 is a perspective view thereof, as seen from the front and right; and

FIG. 8 is a view similar to FIG. 1 illustrating sheets of paper received in the machine.

The broken line showing of sheets of paper in FIG. 8 is for illustrative purposes only and forms no part of the claimed design.

FIG. 5.

FIG. 1.

FIG. 3.

FIG.2.

FIG.4.

FIG.6.

FIG. 7.

FIG. 8.
